his Attorney.

UNITED STATES PATENT OFFICE.

JOHN R. HUNNEMAN, OF WELLESLEY HILLS, MASSACHUSETTS.

INDEXING DEVICE.

Application filed June 25, 1923. Serial No. 647,611.

To all whom it may concern:

Be it known that I, JOHN R. HUNNEMAN, a citizen of the United States, residing at Wellesley Hills, in the county of Norfolk and State of Massachusetts, have invented certain new and useful Improvements in Indexing Devices, of which the following is a specification, reference being had therein to the accompanying drawings.

10 My invention relates to an improved form of indexing device, and has for its object improvements of construction, strength, and stiffness, lightness in weight, cheapness in manufacture and durability.

15 Its chief characteristic is that the index tab has a rigidity throughout, that prevents any tendency to bending or doubling, especially at the edge of the index page, sheet, file or the like. Other characteristics will 20 appear hereinafter.

In the drawings illustrating the principle of my invention and the best mode now known to me of embodying the same in operative structure,

25 Fig. 1 shows my improved index to be fixed to a sheet or page of paper, say a ledger page.

Fig. 2 is an enlarged section of the same on line 2—2 Fig. 1.

30 Figs. 3 and 4 show the separate elements of my tab, before being assembled.

Fig. 5 shows these elements assembled ready to be cut up into tabs of any desired width.

35 Fig. 6 shows a tab of the desired width.

Fig. 7 shows the tab positioned in the desired relation with a ledger page, and ready to be secured rigidly thereto, as shown in Figs. 1 and 2.

40 A long, thin and narrow rectangular strip of stiff material 1, Fig. 3, such, for example, as fibre board, of suitable dimensions, is provided.

Upon its top surface 2 there are parallel 45 longitudinal positioning lines 3; said top surface and the under surface having mucilage thereon.

For the stiffener there is a cover or binder 4 of some thin flexible material, say, a light 50 fabric. In length, the binder is substantially the same as the stiffener, but in width it is greater. Before combining the binder with the stiffener, the binder is folded lengthwise, and in order that it may become fixed not only to the stiffener, but later to one face of

a page to be indexed, the adjacent faces 5, 6, of the two folds 7, 8, are provided with mucilage.

The position of the crease 9 of this fold is such that when the crease is adjacent to the edge 10, Fig. 5, of the stiffener, the outer edge portion of the lower fold 7 of the binder extends beyond the edge of the stiffener and forms a lip 11, Figs. 5, 6, 7 and 2; while the width of the upper fold 8 of the binder may be substantially that of the stiffener.

By moistening one fold, as 5, Fig. 4, of the binder, and pressing it against the bottom of the stiffener, the two become fixed together as shown in Fig. 5, and are in merchantable form. Obviously from this structure, one or more index tabs having the desired width may be cut off, as with shears.

To fix the tab to any particular card 12, Figs. 1, 2 and 7, the top surface 2, Figs. 3 and 5, of the stiffener and the adjacent surface 6, Figs. 4, 5, 6 and 7, of the free fold of the binder are moistened; the top surface of the stiffener is moved under the edge portion of the card 12, Fig. 7, until one of the guide lines 3, desired, coincides with the said edge; and then the pressure of the fingers is exerted against the outside of the 80 folds, causing the gummed surface of the binder and the stiffener to engage, and become fixed to, the opposite sides of the edge portion of the card 12, Figs. 1 and 2, to be indexed.

It is now, at once, obvious that no portion of the tab is flexible; that there can be no bending, or cracking of the tab along the edge of the card, sheet, file or the like; that the tab always "stands up," that is, remains 95 in the plane of the page or file, and is ready to be grasped by the fingers of the person using the index, and that the lip additionally secures the tab to the page or file and serves to obviate interference between the free edge 100 of the stiffener and an adjacent page or file.

It is further plain that the above mentioned construction is simple, strong, stiff, light in weight, cheap to manufacture, and very durable.

The positioning lines are a valuable feature of my invention, in that by means of them, there may result a uniformity in the height in all, or in a group, or groups, of the index tabs used in a book, or a system,

but of course they may be dispensed with if one so wishes.

Desiring to protect my invention in the broadest manner legally possible,

5. What I claim is:-

1. An indexing tab comprising a member of stiff, thin material; lines thereon for positioning the mid-portion of said stiff member in relation to the edge of the sheet or file to be indexed; a binder of flexible fabric folded upon itself, one fold being secured to the under side of said stiff member, and the free fold being coextensive with the top surface of said stiff member; the top surface of the stiff member and adjacent under surface of the free fold of the binder being mucilaged for the purpose of securing these latter surfaces of the tab to the sheet or file.
10. 2. An indexing tab comprising a member of stiff, thin material; a binder of flexible material doubled upon itself, one fold being secured to the under side of said stiff member, and the free fold being coextensive with the top surface of the stiff member; the top surface of the stiff member and the adjacent under surface of the free fold of the binder being mucilaged for the purpose of securing the mid-portion of the stiff member in relation to the edge of the sheet or file.
15. 3. An indexing device comprising a member of stiff material; and a binder of flexible material doubled upon itself; said stiff

member and flexible binder being provided with mucilaged surfaces to secure one surface of the stiff member to one side of the sheet or file to be indexed, and one fold of the flexible binder to the opposite side of said sheet or file, the free edge of said sheet or file lying across said stiff member.

4. An indexing device comprising a stiff member; a binder of suitable material foldable upon itself; said stiff member and flexible member being provided with gummed surfaces whereby the stiff member may be so positioned and secured in relation to the free edge of the sheet or file to be indexed, that said free edge lies across said stiff member.

5. An indexing tab comprising a member of stiff, thin material; a binder of flexible material doubled upon itself, one fold being mucilaged and secured to the under surface of the stiff member, but extending beyond the outer edge of said stiff member to form a securing and protecting lip; the top surface of the stiff member and the adjacent under surface of the free fold of the binder being coextensive and mucilaged for the purpose of securing the top face of the stiff member and the under face of the free fold, to opposite sides of the sheet or file to be indexed.

In testimony whereof I hereunto affix my signature.

JOHN R. HUNNEMAN.
